CARPET NEEDLE

Filed Dec. 19, 1927

Emil J. Seeger
INVENTOR
BY Victor J. Evans

UNITED STATES PATENT OFFICE

EMIL J. SEEBER, OF CHICAGO, ILLINOIS

CARPET NEEDLE

Application filed December 19, 1927. Serial No. 241,160.

This invention relates to certain novel improvements in carpet needles and is particularly directed to improvements in such mechanisms as are adapted for insertion of the weft and still more specifically to an improved construction which will cause self advancing of the needle.

The invention hereinafter described is an improvement on the mechanism described and claimed in my copending application, Serial Number 218,531 filed in the United States Patent Office on or about September 9th, 1927, and the salient object of this invention is to provide an improvement in the construction of the device described in the above named application which will cause the needle, when retracted, to move to a position above the point at which it is to be next inserted.

Another object of the invention is to arrange a device of the foregoing character in such a manner that the operation thereof will be very simple in order that a comparative novice may operate the device and produce a product of uniform quality.

Other objects will appear hereinafter.

The invention consists in the novel combination and arrangement of parts to be hereinafter described and claimed.

The invention will be best understood by reference to the accompanying drawing, showing the preferred form of construction and in which;

Fig. 1 is a side elevational view of a preferred form of construction for my invention in which certain parts are shown in section;

Fig. 2 is a sectional view taken on the line 2-2 on Fig. 1;

Fig. 3 is a sectional detail view taken substantially on the line 3-3 on Fig. 1; and

Figs. 4 to 9 inclusive are partially diagrammatic views depicting the various steps in the operation of my device.

Carpet needles of the type to which my invention relates include a needle having an eye therein and a looper adapted to cooperate with the needle in order to form loops in the rug on the side adapted to be disposed upwardly. The needle and the looper are

carried on structures which are mounted in juxtaposition to each other for relative reciprocal movement. The device disclosed herein is constructed substantially similar to the device described and claimed in my above referred to copending application.

The mechanism comprises a needle 10 which is formed substantially U-shaped and which embodies a pointed end 11. The needle 10 has an eye 12 formed therein adjacent the pointed end 11 and in operation the weft strand is adapted to be inserted through the warp and then a looper is slid along the needle through the warp and engages the weft strand so as to retain said strand in position through the warp when the needle is retracted.

The needle 10 is secured in any desired manner, as by the rivets 13, to the needle member 14. The looper which is indicated by 15 in the drawing is secured as by the rivets 16 to looper member 17. As has been stated the needle is formed substantially U-shaped and the looper 15 is adapted to be so positioned that it will be disposed in said U-shaped needle so as to be reciprocal therein. The members 14 and 17 include the co-extensive portions 18 and 19. In the portion 18 of the needle member 14 a slot 20 is formed and a rivet 21 is mounted in the juxtaposed portion of the portion 19 of the looper member 17. In the portion 19 of the looper member 17 a slot 22 is formed and a rivet 23 is mounted in the juxtaposed portion of the portion 18 of the needle member 14. The slots and rivets are arranged so as to permit relative reciprocation between the portions 18 and 19.

The portion 18 is extended and bent into a substantially S-shaped portion 24 and the portion 19 is extended and is bent into a substantially S-shaped formation 25. The portions 24 and 25 include tangs 26 and 27. The opposite ends of the portions 18 and 19 are extended forwardly and then bent outwardly and rearwardly so as to provide portions 28 and 29 which are adapted to terminate adjacent the tangs 26 and 27. Handles 30 and 31 are disposed around the tangs 26 and 27 and the co-operating portions 28 and 29. The above described construction is substantially

similar to that of my hereinbefore referred to copending application.

I have found that considerable skill is required for proper manipulation of a device as above described since it is difficult for a novice to advance the needle an equal amount prior to each insertion. I have therefore provided a construction which will cause automatic advancing of the needle. By referring to Fig. 1, it may be seen that the needle 10 is secured to the portion 18 of the needle member 14 and that the section of portion 18 to which said needle is attached, is offset as indicated at 32 in the drawings. In the offset portion 32, adjacent the needle carrying end thereof, two outwardly extending lugs 33 and 34 are struck. It will be seen by referring to Fig. 3 that the lugs or humps are disposed on each side of the needle 10 and also that these humps extend toward the portion 19. The rivets 21 and 23 are arranged so as to permit a certain amount of lateral play between the members 14 and 17. Therefore when the needle member 10 is retracted the peak of the humps 33 and 34 engage the point 35 on the looper member 17 and tend to spring said members apart. This action is utilized to cause advancement of the needle in the following manner.

By referring to Figs. 4 to 9 inclusive the manner of operating this needle may be seen. In these views A, B, and C indicate three strands of a warp and it is to be understood that the device is not limited merely to warp strands and further the advance is not limited to a movement of merely one strand, but by regulating the size of the humps 33 and 34 the needle may be caused to advance over any desired number of warp strands dependent upon the coarseness of the warp. W indicates the weft strand.

In Fig. 4 the device is illustrated in the first position, the weft W has been directed through the eye 12 and it is to be understood that the weft will be extended beyond the eye 12 a distance to provide an overhanging portion T which will serve as a retaining portion and which is adapted to be securely anchored so as to prevent withdrawal of the weft strand after insertion. In the first operation and prior to the insertion the looper member 17 is retracted as far as the slots 20 and 22 and the rivets 21 and 23 will permit, thus causing the needle 10 to be extended forwardly. The needle is then inserted between the warp strands A and B and thus a loop L is formed. The next operation is that depicted in Fig. 5 wherein the needle 10 is allowed to remain in its relative position but the looper member 17 is run forwardly so as to bring the portion 36 thereof into engagement with the surfaces of the warp, it being understood that the needle member 14 has been moved forwardly a distance sufficient to bring the portion 37 thereof into engage-

ment with the warp, that is, the portion 37 engages the weft strand and clamps it between said portion 37 and said warp. It will be apparent that the looper 15 moves forwardly through the U-shaped portion of the needle and therefore is disposed so as to retain loop L. It is to be understood that the looper 15 is preferably formed of a resilient material such as flat spring steel. It is apparent that when the looper member 17 moves forwardly the portion 19 thereof rides along the humps 33 and 34 but inasmuch as the looper and the needle will be held in juxtaposed position by the warp strands A and B said looper will be flexed as is indicated in Fig. 5. The next step in the operation of the device is the retracting of the needle while retaining the looper in the position indicated in Fig. 5. The needle in partially removed position is indicated in Fig. 6 and it will be noted that the warp strands A and B are still holding the needle 10 and the looper 15 in substantially juxtaposed position. However, as soon as the needle is withdrawn from engagement with the warp strand B, the resiliency of the looper 15 will cause said looper to tend to straighten which will obviously move the needle 10 beyond the warp strand B and in the present instance into a position above the space between the warp strands B and C. Thus, it will be seen that the needle is advanced an amount equal to the size of the humps 33 and 34 which will obviously be the amount that the looper 15 tends to straighten and therefore move the needle 10.

In Fig. 8 the next step of the operation is depicted. It will be seen that the needle 10 has been inserted between the warp strands B and C and it should be noted that the looper 15 is still retained between the warp strands A and B and is holding the loop L. In Fig. 9 the next step is depicted. Herein it will be seen that the looper 15 has been retracted from the loop L and said loop is free. The next step in the operation will be substantially similar to Fig. 5 and the looper will move into position between the warp strands B and C and the above operations will therefore be repeated.

The proper manner of using the device is to grip the handles 30 and 31 between the fingers of each hand and to allow the thumbs to rest on the portions 38 and 39 and to direct the index fingers along portions 28 and 29. Obviously advance is in the direction of the needle 10 and therefore operation will be begun along the edge of the warp on the looper side. It is apparent that the humps 33 and 34 will cause a uniform advancement and therefore a novice may readily use the device and produce a product of pleasing appearance and uniform quality.

While I have illustrated and described the preferred form of construction for carrying

my invention into effect, this is capable of variation and modification, without departing from the spirit of the invention. I, therefore, do not wish to be limited to the precise details of construction set forth, but desire to avail myself of such variation and modifications as come within the scope of the appended claims.

Having thus described my invention, what I claim as new and desire to protect by Letters Patent is:

1. In a device of the character stated, a substantially U-shaped needle member having portions providing a tang, a substantially U-shaped looper member having portions providing a tang, handles mounted on said tangs, said needle and looper members embodying co-extensive portions having slots formed therein, connecting members carried by said looper and needle members whereby the connecting member on said looper member will extend through the slot in said needle member and the connecting member carried by said needle member will extend through the slot in said looper member to permit relative reciprocation of said members, said needle member having a portion in the co-extensive portion thereof adjacent the bight portion thereof offset away from the co-extensive portion of said looper member, a needle, means for securing said needle to the offset portion of said needle member whereby a portion of said needle will project beyond the bight portion of said needle member, said needle member having humps formed thereon in the offset portion on each side of said needle, said humps extending toward said looper member, a looper adapted to co-operate with said needle, means for securing said looper to said looper member whereby a portion of said looper will project beyond the bight portion of said looper member, said humps serving to move said looper member laterally with respect to said needle member during said relative reciprocation after said looper has advanced beyond said needle member whereby said resilient looper will be flexed as said looper member is moved forwardly with respect to said needle member.

said looper member, a needle, means for securing said needle to the offset portion of said needle member whereby a portion of said needle will project beyond the bight portion of said needle member, said needle member having humps formed thereon in the offset portion on each side of said needle, said humps extending toward said looper member, a looper adapted to co-operate with said needle, means for securing said looper to the co-extensive portion of said looper member adjacent the bight portion thereof whereby a portion of said looper will project beyond the bight portion of said looper member, said humps serving to move said looper member laterally with respect to said needle member during said relative reciprocation after said looper has advanced beyond said needle member whereby said resilient looper will be flexed as said looper member is moved forwardly with respect to said needle member.

In testimony whereof I affix my signature.
EMIL J. SEEBER.
